FIREARM FOR RIM-FIRE CARTRIDGES

Frank F. Burton, Mount Carmel, Conn., assignor
to Winchester Repeating Arms Company, New
Haven, Conn., a corporation of Maryland

Application February 4, 1933, Serial No. 655,155

6 Claims.

(Cl. 42—2)

This invention relates to improvement in firearms, and particularly to that class of firearms designed for the use of so-called "rim-fire" cartridges, that is to say, cartridges which are fired by a blow from an eccentrically-positioned firing-pin or the like delivered upon their rear faces at a point adjacent the peripheries thereof.

As previously constructed, a firearm for rim-fire cartridges has usually been provided with a firing-pin having a flat or wedge-shaped impact-point which has a tendency to shear the rear wall of the cartridge being used and has served to pinch the rim of the cartridge against a surface extending substantially at a right angle to the axis of the cartridge. This and similar constructions have oftentimes occasioned the rupturing of the cartridge, particularly at the periphery of its rim, where the metal is already stretched, due to its being bulged outwardly and folded during the manufacture of the cartridge to form such rim and the annular recess therein for the reception of the priming-compound.

Efforts have heretofore been made to overcome the objections above-referred to but with more or less indifferent results, inasmuch as efforts to avoid the rupturing of the cartridges have often resulted in decreasing the sureness of firing and vice versa.

One of the objects of the present invention is to provide a firearm for rim-fire cartridges in which the danger of rupturing rim-fire cartridges, by reason of the impact of the firing-pin thereupon, may be practically eliminated without, however, sacrificing sureness of firing.

Other objects and advantages will appear to those skilled in the art from the following, taken in conjunction with the accompanying drawing and the appended claims.

In the accompanying drawing:

Fig. 1 is a broken view in central longitudinal section of the rear end of the barrel and adjacent portions of a firearm for rim-fire cartridges, a loaded cartridge being shown in place in the firing-chamber and the firing-pin being shown as retracted, preparatory to engaging and firing the cartridge;

Fig. 2 is a view corresponding to Fig. 1 but showing the firing-pin engaged with the cartridge which has thus been fired; and

Fig. 3 is a view in rear-end elevation of the barrel, showing a fired cartridge in the cartridge-chamber thereof.

The particular firearm herein chosen for the illustration of my invention includes a barrel 10 having an externally-threaded shank 11 engaged

with an internally-threaded socket 12 in the receiver or body-member 13 of the arm.

Movable in the receiver in the usual manner of bolt-action firearms, is a breech-bolt 14 carrying a reciprocating firing-pin 15 having a spherically-contoured impact-point 16 eccentrically positioned with respect to the axis of the barrel 10 and hence with respect to the axis of a cartridge-chamber 17 in the rear portion thereof.

The firing-pin 15, above referred to, cooperates with a firing-anvil 18 in such manner as to simultaneously pinch and bend a portion of the rim 19 of a rim-fire cartridge 20 to detonate a body of priming-mixture 21 located within the rear end of the cartridge and extending outwardly into an annular recess 22 within the said rim, as will hereinafter appear. Preferably, the center line or axis of the eccentrically-positioned firing-pin 15 is located well within the periphery of the rim 19 to such a degree as to intersect the cartridge-chamber 17.

The firing-anvil 18 before referred to forms the bottom of an annular rim-receiving recess 23 in the rear end of the barrel 10 and slopes inwardly and forwardly to intersect the cartridge-chamber 25 17 in the said barrel which receives the cartridge 20 as shown.

For the purpose of convenience of manufacture, the sloping firing-anvil 18 is annular in form though, obviously, the said anvil may be merely of local extent, so long as it is in line with the firing-pin 15 for being coated with thereby in firing a cartridge.

When the firing-pin moves forwardly from the position in which it is shown in Fig. 1 into the position in which it is shown in Fig. 2, the portion of the rim 19 of the cartridge 20 with which it contacts is simultaneously pinched and bent so as to substantially conform to the slope of the firing-anvil 18, as shown in the latter figure. It will be noted by reference to the drawing that the portion 16^a of the spherically-contoured impact-point 16 forms an impact-surface substantially conforming to and complementing the sloping firing-anvil 18 to produce the pinching and bending action just referred to.

The simultaneous pinching and bending action above referred to acts to detonate the priming-mixture 21 with the maximum of certainty without, however, shearing the rear-wall of the cartridge or pinching the rim thereof to such a degree as would cause the rupture of the same either before or after the firing of the cartridge.

In other words, during the firing action and owing primarily to the sloping character of the

firing-anvil 18, the spherically-contoured impact-surface 16^a of the firing-pin 15 will be enabled to forwardly deflect a considerable portion of the rear wall 24 of the cartridge 20, to thus further insure the detonation of the priming-mixture 21, without requiring that the rim 19 of the cartridge be pinched or crushed to such a degree as to weaken the same sufficiently to cause a rupture incident to the explosion taking place within the cartridge. Preferably and as shown, the center line of the firing-pin 15 is located well inside the fold of the rim 18, so that no such strain is placed thereon as would occasion a rupture, as just referred to.

15 The invention may be carried out in other specific ways than that herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

I claim:

25 1. A firearm for rim-fire cartridges, having an inwardly-and-forwardly-sloping firing-anvil adjacent the rear end of the cartridge-chamber therein; and a firing-pin eccentrically-positioned with respect to the axis of the said cartridge-chamber and located in position to simultaneously pinch a portion of the rim of a rim-fire cartridge and bend the same into an angular position substantially corresponding to the slope of the said firing-anvil.

35 2. A firearm for rim-fire cartridges, having an inwardly-and-forwardly-sloping firing-anvil adjacent the rear end of the cartridge-chamber therein; and a firing-pin eccentrically-positioned with respect to the axis of the said cartridge-chamber and having an inwardly-and-forwardly-sloping impact-surface complementing the said sloping firing-anvil and positioned to simultaneously pinch a portion of the rim of a rim-fire cartridge and bend the same into an angular position substantially corresponding to the slope of the said firing-anvil.

40 3. A firearm for rim-fire cartridges, having an inwardly-and-forwardly-sloping firing-anvil adjacent the rear end of the cartridge-chamber

therein; and a firing-pin eccentrically-positioned with respect to the axis of the said cartridge-chamber and having a substantially spherically-contoured inwardly-and-forwardly-sloping impact-surface complementing the said sloping firing-anvil and positioned to simultaneously pinch a portion of the rim of a rim-fire cartridge and bend the same into an angular position substantially corresponding to the slope of the said firing-anvil.

4. A firearm for rim-fire cartridges, having an inwardly-and-forwardly-sloping firing-anvil adjacent the rear end of the cartridge-chamber therein; and a firing-pin eccentrically-positioned with respect to the axis of the said cartridge-chamber but having its own axis intersecting the said chamber, and located in position to simultaneously pinch a portion of the rim of a rim-fire cartridge and bend the same into an angular position substantially corresponding to the slope of the said firing-anvil.

5. A firearm for rim-fire cartridges, having an inwardly-and-forwardly-sloping firing-anvil adjacent the rear end of the cartridge-chamber therein; and a firing-pin eccentrically-positioned with respect to the axis of the said cartridge-chamber but having its own axis intersecting the said chamber, and having an inwardly-and-forwardly-sloping impact-surface complementing the said sloping firing-anvil and positioned to simultaneously pinch a portion of the rim of a rim-fire cartridge and bend the same into an angular position substantially corresponding to the slope of the said firing-anvil.

6. A firearm for rim-fire cartridges, having an inwardly-and-forwardly-sloping firing-anvil adjacent the rear end of the cartridge-chamber therein; and a firing-pin eccentrically-positioned with respect to the axis of the said cartridge-chamber but having its own axis intersecting the said chamber, and having a substantially spherically-contoured inwardly-and-forwardly-sloping impact-surface complementing the said sloping firing-anvil and positioned to simultaneously pinch a portion of the rim of a rim-fire cartridge and bend the same into an angular position substantially corresponding to the slope of the said firing-anvil.

FRANK F. BURTON.
